CLAIM

The ornamental design for an electronic device with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing a first embodiment of the claimed design;

FIG. 2 is a second embodiment thereof;

FIG. 3 is a third embodiment thereof;

FIG. 4 is a fourth embodiment thereof;

FIG. 5 is a fifth embodiment thereof;

FIG. 6 is a sixth embodiment thereof; and,

FIG. 7 is a front view of an electronic device having a display screen with the graphical user interface of FIG. 1 applied to the display screen. The graphical user interface designs of FIGS. 2-6 may be similarly applied thereto.

The broken lines in the figures show a display screen or portion thereof, or an electronic device having a display screen, and form no part of the claimed design.
